UNITED STATES PATENT OFFICE.

JAMES A. SATHER, OF OAKLAND, CALIFORNIA.

VENDING MACHINE.

Application filed August 17, 1925. Serial No. 50,671.

The present invention relates to improvements in vending machines and has particular reference to an automatic vending machine adapted for dispensing gasoline at service stations. It is proposed in the present invention to provide a vending machine of this character that will dispense a certain amount of gasoline or other liquid upon the insertion of a coin and in which provision is made for allowing the quantity dispensed in return for the coin to be changed in accordance with the fluctuations of the market price of the liquid. If the machine, for instance, is intended to be operated by inserting a one dollar piece means are provided for opening a valve for a certain length of time after the one dollar piece has been inserted so that gasoline is allowed to flow for that length of time, suitable means being provided for maintaining a substantially constant head so that the total amount dispensed depends entirely upon the time during which the valve is open. Since the market price of gasoline or other liquid for which the machine may be used fluctuates, it might become necessary to change the amount to be dispensed upon the insertion of a one dollar piece and it is proposed in the present invention to provide means allowing the time period during which the valve is opened to be regulated.

Further objects and advantages of my invention will appear as the specification proceeds.

The preferred form of my invention is illustrated in the accompanying drawing in which Figure 1 shows an end elevation of the entire mechanism, Figure 2 a partly sectional view taken along line 2-2 of Figure 1, Figure 3 a horizontal section taken along line 3-3 of Figure 2 and Figure 4 a vertical section taken along line 4-4 of Figure 3.

While I have shown only the preferred form of the invention, I wish to have it understood that various changes or modifications may be made within the scope of the claims hereto attached without departing from the spirit of the invention.

In its preferred form my device comprises the vessel 1 which is preferably elevated so that gasoline or other liquid may flow through the pipe and the hose 3 into the gasoline tank of a motor vehicle or other receptacle to be filled by gravity. The level of gasoline in the vessel is substantially maintained constant by means of the float 4 operating a valve 6 in the supply pipe 7, undue rising of

the level due to leakage in the valve 6 or other causes being prevented by the overflow pipe 8.

Where the hose 3 connects with the pipe 2 a fitting 9 is introduced which includes a valve 11 on the valve seat 12, the valve being arranged to present a stem 13 which has a link 14 pivoted to the end thereof the free end of the link 14 being pivoted to a suspended link 16. The latter is normally pulled toward the valve fitting by means of a spring 17 which tends to keep the valve closed. A rod 18 is threaded into the link 16 so as to extend substantially parallel to the valve stem into the path of a revolvably mounted element 19. The latter is arranged co-axially with a spring 21 which tends to revolve the element 19 while a pawl 22 fixed to the shaft 23 is adapted to engage with any one of a plurality of notches 24 in a second wheel 26 mounted co-axially with the element 19 for preventing the common shaft from revolving. The shaft 23 on which the pawl 22 is fixed is provided with a crank hand 27 adapted to be operated by raising the vertical rod 28 in a manner to be described hereinafter.

It will be seen from this description that when the rod 28 is raised, the pawl 22 is lifted out of whatever notch it is engaged with and allows the spring 21 to revolve the element 19 which in the drawing is presented as having three arms 29 with the rod 18 extending into the path of one of them. As the element 19 begins to rotate the arm 29 lifts the rod 18 and thereby opens the valve 11, allowing gasoline to flow therethrough. The valve remains open until the rod 18 drops out of engagement with the arm 29 whereupon it is closed by the spring 17. The period of time during which the valve remains open may be changed by adjusting the threaded rod 18, the time being made longer when the rod 18 is screwed outwardly and shorter when the rod is screwed inwardly.

To aid the pawl 22 in stopping the wheel 26 when reaching the first notch thereon it may be advisable to apply a second pawl 31 to a wheel 32 on the shaft 33 which is operated from the shaft 20 of the revolving element 19 through reducing gears 34 and 36. A fan 37 on a shaft 38 receiving rotary motion from the shaft 33 through the gears 39 is adapted to reduce the speed of the shaft 20 and the revolving element 19. The spring 21 may be wound by revolving the shaft 20 by means of a suitable key engaging the angular end 41

thereof, a spring 42 allowing the element 19 to be pushed inwardly out of the path of the rod 18.

The vertical rod 28 terminates at its lower end in a wedge 43 which is normally forced downward by the spring 44. The same may be raised by the slide 46 arranged on the platform 47 and normally drawn backward by the spring 48 on the pin 49 which rides in a slot in the slide. The rear end of the slide terminates in a semi-circular opening 51 adapted to accommodate within the confines thereof the particular coin for which the device is designed as, for instance, a one dollar piece. A second slide 52 is arranged on the same platform and provided with a similar recess 53 in the front end thereof so that a one dollar piece may be placed on the platform in front of the slide 52, pushed forward into engagement with the slide 46 whereupon on further forward motion it will force the slide 46 under the wedge 43 and thereby raise the rod 28 for the purpose previously described. The platform 47 is provided with a gate 54 hinged to the platform as shown at 56 with a spring 57 serving to normally close the gate. The latter is formed with an opening 58 sufficiently large to allow a smaller coin to drop therethrough while a one dollar coin may ride on the edges of the opening. In this manner provision is made that only the proper coin will operate the device. When the slide 46 has been slid forward by the aid of the one dollar piece and through the chain of connections previously described has released the revolving element 19 one of the arms of the latter depresses a lever 59 pivoted to a standard 61 and connected with its free end to a plunger 62 adapted to bear down on an extension 63 of the gate 54 whereby the latter is opened and allows the coin to drop therethrough. A guard 64 overlying the slide 46 guides the upper face of the coin.

The operation of the device is as follows:

A person desiring to buy a dollar's worth of gasoline places a one dollar piece on the platform 47 in front of the slide 52 and pushes the latter forward whereby the one dollar piece is pushed against the rear face of the slide 46 and pushing the latter ahead raises the rod 28. This causes the shaft 23 to be revolved whereby the two pawls 31 and 22 are disengaged from the wheels 32 and 26 respectively, so that the wheel 26, and with it the element 19 are free to revolve under the influence of the spring 21. While thus revolving the arm 29 raises the rod 18 of the valve mechanism and opens the latter so as to allow gasoline to flow through the tube into the gasoline tank of a motor vehicle. The speed of the revolving element 19 is reduced through the chain of reduction gears and the fan 37. The valve 11 remains open until the rod 18 drops from the arm 29 and this period of time can be regulated by ad-

justing the rod 18 in the suspended link 16. The revolving of the element 19 further causes the lever 59 to be depressed whereby the gate 54 is opened and the one dollar piece allowed to drop into the container provided for the same. The spring 57 automatically closes the gate as the pressure of the arm is released. When the element 19 has revolved sufficiently far for the pawl 22 to reach the second notch 24, the pawl will engage with the same and stop the revolving motion. The pawl 22 is hereby aided by the pawl 31 which may be arranged to arrest the progress of the wheel 32 at each revolution thereof in the well known manner of a clock mechanism. 80

Having described my invention, what I claim is:

1. In a liquid vending device of the character described, a control valve, an operating mechanism adapted to become active for a predetermined period of time upon the insertion of a coin, an operative connection between the mechanism and the valve for operating the latter, the latter connection being adjustable to allow the valve period to be regulated independently of that of the mechanism, said operating mechanism comprising a revolving element actuating said operative connection, spring means to revolve the revolving element, and releasable means to arrest the motion of said element. 90

2. In a liquid vending device of the character described, a control valve, an operating mechanism including a revolving element, means to revolve the revolving element for a predetermined period; means to arrest the motion of said revolving element, means to release said arresting means upon the insertion of a coin; and an operative connection between the revolving element and the valve made for operating the latter for a period independent of the period of the revolving element. 105

3. In a liquid vending device of the character described, a control valve, an operating mechanism including a revolving element; means to actuate said revolving element, means to arrest the motion of the element, means for rendering the revolving means active for a predetermined period upon the insertion of a coin; and an operative connection between the revolving element and the valve for operating the latter, made adjustable so as to allow the valve period to be regulated independently of the period of the revolving element. 115

4. In a liquid vending machine, a valve control comprising an axially movable valve, an operating link pivoted thereto, a suspended link pivoted with its free end to the operating link having a rod extending therefrom, spring means tending to close the valve; a revolving element engaging with the rod for a predetermined period for operating the valve, spring means tending to revolve said revolving ele- 125 130

ment, and releasable means to arrest the revolving motion of said element.

5. In a liquid vending machine of the character described, a revolvably mounted element, spring means tending to revolve the same, a pivoted element mounted for engagement with the revolving element for arresting its revolving motion, a vertical rod adapted to operate the pivoted element for releasing 10 the revolving element, a sliding wedge and means cooperating with an inserted coin for engaging the wedge with the rod whereby the latter is lifted.

6. In a device of the character described, 15 an operating element having a wedge-shaped bottom, a slide engageable therewith for raising the operating element and coin-controlled means for advancing the slide.

7. A device as defined in claim 6 in which a trap door is provided below the slide and in 20 which means are provided for opening the trap door when the coin has advanced the slide.

8. In a device of the character described, a dispensing valve, an operating element for 25 the same, coin-controlled means rendering the latter active, a coin trap comprising a gate operatively associated with the coin-controlled means so as to be actuated thereby for opening the gate thus dropping the coin 30 when the same has performed its function, and means to hold said gate in closed position.

In testimony whereof I affix my signature.

JAMES A. SATHER.
